(57) **CLAIM**

The ornamental design for a helical sleeve of an anchor, as shown and described.

DESCRIPTION

FIG. 1 is a perspective view of a helical sleeve of an anchor according to the design;

FIG. 2 is an additional perspective view thereof;

FIG. 3 is a bottom view thereof;

FIG. 4 is a side view thereof; and,

FIG. 5 is an additional side view thereof.

The dot-dash-dot broken lines and the dot-dot broken line showing of the anchor illustrates the environment of the claimed design and forms no part thereof.

1 Claim, 5 Drawing Sheets
